UNITED STATES PATENT OFFICE.

ESTELLE A. KRONER, OF ST. LOUIS, MISSOURI.

PHOTOPRINT-DRIER.

1,277,952.

Specification of Letters Patent. Patented Sept. 3, 1918.

Application filed November 24, 1917. Serial No. 203,720.

To all whom it may concern:

Be it known that I, ESTELLE A. KRONER, a citizen of the United States, residing at St. Louis, State of Missouri, have invented 5 certain new and useful Improvements in Photoprint-Driers, of which the following is a specification.

This invention relates to machines or apparatus for drying photo prints or other 10 similar articles, and is particularly directed to improvements in the construction of machines of the character shown in my co-pending application filed July 10, 1916, Serial No. 108,261.

15 The objects of this invention are to improve the construction of photo print driers; to provide a novel arrangement for keeping the belts alined on the drum and rollers; to provide simple and efficient devices for automatically taking up the slack in the belts 20 and giving them a sufficient tension; and in general, to provide such advantages and improvements in construction as will be described more fully hereinafter.

25 In the accompanying drawings illustrating this invention,

Figure 1 is a side view of my improved machine;

Fig. 2 is a plan view;

30 Fig. 3 is a detail showing the guiding cord which is bound in the side of the belt.

As shown in these drawings, 4 indicates 35 a frame of any suitable construction in which is mounted a relatively large heating or drying drum 5. This drum may be heated in any well known manner. This drum is mounted in bearings 6, and is provided with a worm wheel 7 for turning the same. The wheel 7 is engaged by worm 8 on a 40 shaft 9 which is supported by suitable bearings in the frame and is provided with a worm wheel 10 adjacent to the lower end thereof. This wheel is driven by a worm 11 on the shaft of a motor 12. This provides a simple form of drive, and gives the 45 proper reduction in speed as the drum is driven at a comparatively slow speed. A belt or apron 13, which is made of suitable absorbent material such as cloth or the like, 50 passes around the drum 5, and then around a guide roller 14, and then back and around guide rollers 15, 16, 17, and 18, in the manner shown in Fig. 1. The guide roller 14 is mounted in arms 19, which extend outwardly and forwardly at the top of the

frame, and are secured by means of bolts 20 and 21 so that they may be removed or swung up or down to enable the machine to pass through a relatively narrow doorway. Two arms 22 are pivoted at 23 to a frame 4, 60 and are provided at their outer ends with adjustable weights 24. These arms carry a roller 25 which engages the belt 13, and presses downwardly on the portions between the rollers 14 and 15, thereby taking up any 65 slack in this belt, and giving it the necessary tension.

A second belt or apron 26, similar in character to the belt 13, passes substantially around the drum 5, overlying the belt 13, 70 and then around guide rollers 27, 28, 29, 30, 17 and 18, as shown in Fig. 1. Two arms 31 are pivoted at 32 to the frame 4, and are provided with adjustable weights 33. These arms carry a roller 34 which engages with 75 the portion of the belt 26 between the rollers 29 and 30, and takes up any slack in this belt; and gives it the necessary tension.

The difficulty of keeping wide belts in proper alinement when running over pulleys, or when operating in a machine of this character, is well understood, and one of the principal features of this invention consists in the means provided for holding these belts in proper position on the drum and 80 guide rollers. As shown in Fig. 3, the edges of the belt 13 are provided with cords or ropes 35 which are secured thereto in any convenient manner, as by being sewn in the hems of the belt. These ropes not only 85 strengthen the belt, but form longitudinal guides therefor. These guides are engaged by grooved pulleys or wheels 36 and 37 at each side of the machine. These pulleys are mounted on brackets 38 so that the ropes 90 run between the respective pairs. Any number of these guide pulleys may be used, but I have found that two sets or pairs arranged at the top of the machine are sufficient. The belt 26 is provided with similar 95 ropes 39 which are engaged by pulleys 40 and 41 mounted on brackets 42 at the back of the machine, this arrangement serving to guide the outer belt. A removable box 43 is arranged to receive the dried prints. 100

The prints or other articles to be dried are fed into the machine on the feeding area or table provided by the portion of the belt 13 between the rollers 14 and 27. The prints are carried in between the two 110

belts, then around the drum where they become dried, and then pass out between the rollers 16 and 17 and are discharged into the box 43. The reverse curve formed by 5 the rollers 17 and 18 tends to straighten the prints after they have been curved in passing around the drum.

Having thus described my invention, what I claim and desire to secure by Letters Patent is:

1. In a photo print drier, the combination of a frame, a heater drum mounted in said frame, detachable arms extending outwardly at the top of the frame, a guide roller carried by said arms, and a belt engaging with said roller and said drum, the arrangement being such that guide roller and arms may be adjusted or removed from the main frame.
2. In a photo print drier, the combination of a heater drum, means for turning said drum, a pair of belts coacting with said drum for carrying the prints around the same, guide rollers for said belts, longitudinal guides on said belts, and means engaging with said guides for holding the belts in alinement.
3. In a machine of the character set forth, the combination of a heater drum, means 30 for turning said drum, a pair of belts coacting with said drum, guide rollers for said belts, ropes secured at the edges of said belts, and wheels engaging with said ropes for holding the belts in alinement on the drum and rollers.

4. In a photo print drier, the combination of a frame, a heater drum mounted in said frame, means for turning said drum, a belt of absorbent material passing around said drum, guide rollers for said belt, a 40 second belt passing around said drum and superimposed over the first named belt, guide rollers for said second belt, ropes sewn in the hems of each of said belts, and grooved wheels arranged in pairs on the 45 said frame and engaging with the portions of the belts containing said ropes for holding said belts in alinement on the drum and rollers.

5. In a photo print drier, the combination of a frame, a heater drum mounted in said frame, guide rollers mounted in said frame, detachable arms secured to the top of the frame, a guide roller mounted in said arms, a belt engaging with said drum 55 and said guide rollers, ropes sewn in the hem of said belt, grooved wheels secured to said frame and engaging with the hems of the belt, an automatic tightener for said belt, a second belt engaging with said first 60 named belt and passing partially around said drum, a plurality of guide rollers for said second named belt, ropes sewn into the hem of said second named belt, grooved wheels secured to said frame and engaging 65 with the hems of said second named belt, and an automatic tightener for said second named belt.

ESTELLE A. KRONER.
